US00D785660S

(12) **United States Design Patent** (10) **Patent No.:** **US D785,660 S**
Kim et al. (45) **Date of Patent:** **** May 2, 2017**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Sae-Mi Kim**, Goyang-si (KR); **Jung-Ah Seung**, Guri-si (KR); **Mi-A Oh**, Seongnam-si (KR); **Tae-Hyoung Cho**, Seoul (KR)

(73) Assignee: **Samsung Electronics Co., Ltd.**, Suwon-si (KR)

(**) Term: **15 Years**

(21) Appl. No.: **29/562,081**

(22) Filed: **Apr. 22, 2016**

(30) **Foreign Application Priority Data**

Dec. 23, 2015 (KR) 30-2015-0066008

(51) LOC (10) Cl. **14-04**

(52) U.S. Cl.

USPC **D14/486**

CLAIM

We claim the ornamental design for a display screen or portion thereof with graphical user interface, as shown and described.

DESCRIPTION

The sole FIGURE is a front view of a display screen or portion thereof with graphical user interface showing our new design.

The dot-dot-dash broken lines depict a display screen or portion thereof and form no part of the claimed design.

1 Claim, 1 Drawing Sheet
